P. S. Emerson.
INVENTOR
BY Victor J. Evans
ATTORNEY

UNITED STATES PATENT OFFICE.

PAUL SALISBURY EMERSON, OF TOTTENVILLE, NEW YORK.

GARMENT-HANGER.

1,399,707.

Specification of Letters Patent.

Patented Dec. 6, 1921.

Application filed September 13, 1920. Serial No. 409,874.

To all whom it may concern:

Be it known that I, PAUL S. EMERSON, a citizen of the United States, residing at Tottenville, in the county of Richmond and 5 State of New York, have invented new and useful Improvements in Garment-Hangers, of which the following is a specification.

My present invention has reference to an improved garment hanger.

10 An object is to produce a garment hanger constructed of a single strand of wire, the lower strands of which being so associated as to provide one of the same with a clamping arm having a hooked end to engage with 15 the other strand and the hook of the hanger being hingedly connected to the body thereof, whereby the hook may be folded against the body when the device is not in use so as to provide a comparatively small bundle for 20 storage or shipment.

The foregoing, and other objects which will appear as the nature of the invention is better understood, may be accomplished by a construction and combination of parts, 25 such as is disclosed by the drawings:

In the drawings:

Figure 1 is an elevation of the improvement, the dotted lines showing the jaw member brought out of engagement with the 30 base member.

Fig. 2 is a similar view but showing the hook folded against the body.

My improved hanger is in the main, constructed from a single strand of wire of a 35 suitable gage, but has the hook 1 thereof hingedly connected to the body 2. The hook is constructed in the usual manner, comprising two strands of wire bent upon themselves to provide the rounded or hooked portion and from thence continued straight, 40 and the said straight portions are connected by a loop 3 that engages with a similar loop 4 on the central straight portion or stem 5 of the body 2. From the stem, the body 45 is extended at opposite downward inclinations providing the upper members or arms 6 of the said body. The arms, at their outer ends are rounded upon themselves, as at 7 and continued inwardly in parallelism. One 50 of the lower portions or arms is indicated

for distinction by the numeral 8, and this member 8 has its end terminating near the rounded end of the second base member 9 and coiled, as at 10, around the said member 9. The member 9 is not otherwise connected to the member 8, the said member 9 having its free end formed with an offset hook 11 to engage with the member 8 when the member 9 is sprung against the member 8. The member 9 thus provides a clamp 60 which will effectively sustain a garment between the same and the member 8. In reality, the members 8 and 9 provide jaws between which the garment is clamped. The clamping members engage trousers or the 65 like, and the angle upper portion of the support receives a coat, vest, etc. thereon, in the usual manner.

It is thought that the foregoing description, when taken in connection with the 70 drawings, will fully set forth the simplicity of the construction and the advantages thereof.

Having thus described the invention, what I claim, is:

A garment hanger of the character described comprising a body and a hook, said body and hook portion being constructed from a single strand of wire, the body having its upper portion terminating to form 80 a stem and having a looped end, the hook portion providing a stem which has a looped end to engage with the loop of the body, said body from the stem being extended at opposite downward inclinations providing 85 the upper members of said body, said upper members at their outer ends being rounded upon themselves and continued inwardly in parallelism, one of said members having its ends terminating near the rounded end of 90 the second base member and coiled therearound, an offset hook provided on said base member at its free end to engage with one of the upper members, clamping means provided by the base member to effectively 95 sustain a garment between said base member and the upper members.

In testimony whereof I affix my signature.

PAUL SALISBURY EMERSON.
